UNITED STATES PATENT OFFICE.

WILLIAM H. VON HAGEL, OF BALTIMORE, MARYLAND.

OIL BURNER.

Application filed August 20, 1925. Serial No. 51,292.

To all whom it may concern:

Be it known that I, WILLIAM H. VON HAGEL, a citizen of the United States, residing at Baltimore city, and State of Maryland, have invented new and useful Improvements in Oil Burners, of which the following is a specification.

This invention consists in certain improvements I have made to oil burners for use in domestic furnaces of all kinds.

Oil burners of this type are well known and there are many of them on the market. They are either of the force feed type, comprising a blower; the natural draft type, or of the type using a spray of steam mixed with the oil.

My invention is a burner of the natural draft type and comprises, as usual, an oil pan having central air openings and an overflow outlet adapted to receive the oil through a central pipe, a skirt depending from and surrounding the pan and by which the burner is supported on the grate, a spreader onto which the oil is fed, and a cap sitting on said spreader, whereby an annular flame is produced.

In the practical use of such burners, I have noticed certain defects or objectionable features, to remove or obviate which is the purpose of the hereinafter described improvements constituting my invention.

Burners of this type have heretofore, as far as I am aware, been merely placed upon the grate and secured in place by the fire clay packing, no means having been provided for leveling them or positively securing them in place. Furthermore, the skirt has merely surrounded the edge of the pan, the clay packing being depended upon to prevent air passing up around the skirt. I have found, however, that air leaks very soon developed, the clay becoming loosened from the periphery of the skirt. Furthermore, it has been customary to screw the spreader onto the end of the oil inlet pipe which projects through the center of the pan. Therefore, when it became necessary to remove or renew the spreader, the inlet pipe would fall down and it became necessary to open up the front of the furnace before a new spreader could be connected. All these disadvantages are obviated by the present improved construction. These improvements are illustrated in the accompanying drawing, in which,

Figure 1 is a central vertical section

through the burner on line 1—1 of Fig. 2, and

Figure 2 is a plan view, with a portion of the cap broken away.

In these views, 1 represents the leveling ring; 2 the pan with central hub 3, surrounded by air openings 4; 5 the skirt or draft cylinder by which the burner is supported on the grate 6; 7 the oil spreader of usual construction, with a threaded stem 8, screwing into hub 3; 9 the oil inlet pipe threaded into the lower end of said hub, and 10 the cap which sits on the spreader.

The ring 1 is leveled by means of the four screws 11 and is then clamped down to the grate by the two bolts 12, passed through a plate or strip 13, beneath the grate bars. The screws 11 bear on steel plates 14.

The pan 2 is flanged, as shown, to rest on the ring and the skirt 5 fits between the wall of the pan and the inside of the ring. This construction prevents any air leakage around the skirt.

The pan has the usual overflow opening 15, connected by a pipe, not shown, with a check-valve bucket to shut off the oil if the flame is extinguished. When it becomes necessary to renew the spreader, it can be unscrewed from the hub 3 without disturbing the oil inlet pipe 9. The vibration, incident to the operation of the burner, cannot cause it to become loose or shift its position and, consequently, there is no danger of air leaks developing. If at any time the pan needs leveling, the screws 11 are available for easy manipulation.

Having thus described my invention what I claim is:

1. In an oil burner, the combination with a flanged pan having a hub for engagement with a spreader and oil inlet pipe, of a ring engaging under the flange of said pan, an annular sheet metal skirt, the upper edge of which fits between said ring and pan under the flange of the latter, and bolts adjustably supporting said ring from the grate.

2. An oil burner, comprising a cylindrical skirt adapted to rest on the grate of a furnace, a flanged pan resting on the upper edge of said skirt, a ring surrounding said upper edge and engaging the underside of said flange, screws threaded through said flange and abutting the grate, and bolts to clamp said ring to said grate.

3. An oil burner for domestic furnaces

comprising a cylinder adapted to seat on of said pan to clamp it and said cylinder the grate, a flanged pan adapted to be sup- to the grate, and leveling screws for said ported on the top edge of said cylinder, pan abutting said grate. 10
an oil spreader centrally supported in said In testimony whereof I have hereunto set 5 pan, the latter having air passages leading my hand.
from the grate to the underside of said spreader, bolts passed through the flange
